UNITED STATES PATENT OFFICE.

HIRAM H. SPONENBURG, OF GURNEE, ILLINOIS, ASSIGNOR, BY MESNE ASSIGNMENTS,
TO OTTO R. BARNETT, OF CHICAGO, ILLINOIS.

ANTICREEPER.

1,215,426.

Specification of Letters Patent. Patented Feb. 13, 1917.

Application filed May 29, 1916. Serial No. 100,453.

To all whom it may concern:

Be it known that I, HIRAM H. SPONENBURG, a citizen of the United States, residing at Gurnee, in the county of Lake and State 5 of Illinois, have invented certain new and useful Improvements in Anticreepers, of which the following is a specification.

My invention relates to anti-creepers or devices for preventing the longitudinal 10 creep of railroad rails and the principal object of the invention is to provide an anti-creep, comprising a spring member to bear against and bite into the rail, the parts of which are so constructed and arranged that 15 a forward creeping tendency on the part of the rail checks itself by increasing the spring pressure and the bite of the device on the rail, while any tendency to retrograde movement of the parts due, for example, to 20 vibration, the contraction of the rail at low temperatures, or the reaction of the rail after the forward creeping impulse ceases, is positively prevented.

The invention consists in the constructions, arrangement and devices to be herein-after described and claimed for carrying out the above stated object and such other objects as will appear from the following specification.

30 The invention is illustrated in certain preferred embodiments in the accompanying drawings, wherein—

Figure 1 shows in elevation an anti-creep constructed in accordance with my 35 invention as applied to a rail, the rail being shown in section.

Fig. 2 is a plan view of the parts of the device shown in Fig. 1.

Figs. 3, 4 and 5 are views in perspective 40 of the parts of the anti-creep.

Fig. 6 is a similar view of a modified form of spring member.

Fig. 7 is a plan view of an anti-creep having the modified form of spring, and

45 Fig. 8 is a sectional view on line 8—8 of Fig. 7.

Like characters designate like parts in the several figures of the drawings.

50 Referring first to Figs. 1 to 5 inclusive, the rail is shown at A and the cross-tie against which the anti-creep is abutted at B. In this connection it is to be noted that while I have implied in the specification and claims that the anti-creep bears against a cross-tie, it might obviously be made to abut

against any other fixed element of a road bed.

The form of the invention shown in the first five figures consists of three parts, a bowed spring member 10, a yoke or strap 11 and a 60 foot or tie-abutting member 12. The spring member bears against one edge of the base flange 13 of the rail. The end adjacent tie B is formed preferably with an acute angle bend 14 having therein a notch 15 fitting 65 the edge of the base flange. The spring member is formed so as to diverge from and then curve somewhat sharply around toward the rail, the other extremity of the spring remote from the tie being notched at 16 to 70 fit the base flange. The yoke member 11 has one end turned up to form a jaw 17 for engagement with the base flange. The other end is formed with a larger jaw 18 which extends around the spring 10. The jaw 75 preferably has a lip 19 which comes down close to the upper surface of the rail base.

The foot member 12 is preferably, although not necessarily, made separate from the yoke member 11. As shown, it 80 consists of a piece of steel bent into angular form with the horizontal plate 20 provided with a narrowed portion or tongue 21 adapted to lie in the depressed seat 22 formed in the yoke 11. With the device in place the 85 portions of the yoke 23 on opposite sides of the seat 22 bear against the shoulders 24 on the horizontal plate of the foot member.

In applying the device to a rail the foot member 12 is placed against the tie B and 90 the yoke thrust under the rail from the side engaged by the jaw 17 of the yoke. The spring member 10 is then forced between the jaw 18 of the yoke and the rail as far as it will go in the direction toward the tie. 95 This can be accomplished by bending the spring member inwardly toward the rail base and working it forward little by little. The spring member for most of its length diverges from the rail in the direction away 100 from the tie so that if the rail starts to creep the spring action of member 10 and its bite into the rail is increased. The forward creeping tendency of the rail is, therefore, self-checked since the yoke bears 105 against the shoulders 24 of the foot member 12. On the other hand, there is no danger of the engagement of the yoke and spring member with the rail being loosened. If the rail contracts, the spring and yoke mem- 110

ber will move backwardly away from the tie with it and this will be so even though, as may happen, the foot member is embedded and possibly frozen in the ballast so as to be immovable. The spring pressure exerted by the member 10 against the yoke prevents those parts from being disturbed by vibration or other cause. Even if the foot were made rigid with the yoke the force of the spring ought to be sufficient, under ordinary conditions, to prevent the spring, when moving with the rail away from the tie, from backing out of operative engagement with the yoke. It is preferable, however, to have the sliding relation between the yoke and foot member so that the yoke and spring may move freely with the rail without reference to the foot member. The hold of the device is considerably enhanced by the clawlike notches 15, 16 of the spring which bite into the upper slanting face of the rail base. In the modification shown in Figs. 6 to 8 inclusive, the end of the spring member remote from the tie 25 B is formed with a pronounced bow or curve, as indicated at 26, the other end of the spring 27 lying substantially parallel to the rail. This arrangement shortens the spring and brings the yoke closer to the tie, making the horizontal plate 28 of the foot member 29 shorter than in the other form of the device. In other respects the modified construction may be the same as that shown in the first five figures.

35 I claim:

1. An anti-creeper comprising a spring member, the extremities of which are notched for engagement with the edge of the base flange of a rail, and means for binding the same against the rail.
2. An anti-creeper comprising a spring member adapted to engage a rail at opposite ends, and means provided with a tie-abutting foot for binding said spring member against the rail.
3. An anti-creeper comprising a spring member, the extremities of which are notched for engagement with the edge of the base flange of a rail, and means provided with a tie-abutting foot for binding said spring member to the rail.
4. An anti-creeper comprising a spring member to bear against a rail, means for engaging the same with the rail and a foot member to bear against the tie with which said rail-engaging means has free sliding engagement.
5. An anti-creeper comprising a spring member, the extremities of which are notched for engagement with the base flange of a rail, engaging means which extends around the spring member and rail to bind the spring member to said rail, and a foot member to bear against a tie with which said engaging means has free sliding relation.

6. An anti-creeper comprising a spring member, the ends of which are adapted to bear against a rail, a yoke extending around said spring member and the opposite side of the rail, and a foot member formed with a tie-abutting flange and with a tongue which intervenes between the yoke and the rail base. 70

7. An anti-creeper comprising a spring member, the ends of which are adapted to bear against a rail, a yoke extending around said spring member and the opposite side of the rail, and a foot member formed with a tie-abutting flange and with a tongue which intervenes between the yoke and the rail base with which the yoke has a free sliding relation. 75

8. An anti-creeper comprising a spring member, the extremities of which are notched for engagement with the base flange of a rail, a yoke which extends around the rail and said spring member, and a foot member formed with a tie-abutting flange and with a tongue which extends between the yoke and the rail base. 80

9. An anti-creeper comprising a spring member, the extremities of which are notched for engagement with the base flange of a rail, a yoke which extends around the rail and said spring member, and a foot member formed with a tie-abutting flange and with a tongue which extends between the yoke and the rail base, said yoke being formed with a depressed seat for the tongue. 85

10. An anti-creeper comprising a spring member, the extremities of which are notched for engagement with the base flange of a rail, a yoke which extends around the rail and said spring member, a foot member formed with a tie-abutting flange and with a tongue which extends between the yoke and the rail base, said yoke being formed with a depressed seat for the tongue, and a foot member with shoulders against which the yoke is adapted to bear. 90

11. An anti-creeper comprising a tie-abutting member, a bowed spring member which engages one edge of the base flange of a rail, the intervening portion of which diverges from the rail in the direction backwardly from the tie, and a yoke which extends around the rail and spring member putting the latter under strain against the former. 105

12. An anti-creeper comprising a tie-abutting member, a bowed member notched at opposite ends for engagement with the base flange of a rail, the portion of which between the notched extremities diverges from the rail in the direction backwardly from the tie and a yoke which extends around the rail and spring member, putting the latter under strain against the former. 115

13. An anti-creeper comprising a flat bar of metal formed at one end with a jaw to 120

- engage one edge of the base flange of a rail and at the opposite end with a larger jaw, and a bowed spring member notched at its extremities, which is strained and held in engagement with the base flange of the rail by said last named jaw, said device being provided with a tie-abutting flange.
14. An anti-creeper comprising a flat bar of metal formed at one end with a jaw to engage one edge of the base flange of a rail, and at the opposite end with a larger jaw, a bowed member notched at its extremities, which is strained and held in engagement with the base flange of the rail by said last named jaw, and a foot member provided with a tie-abutting flange and with a tongue which intervenes between the yoke and the bottom on the under surface of the base flange of the rail.
15. An anti-creeper comprising a flat bar of metal formed at one end with a jaw to engage one edge of the base flange of a rail, and at the opposite end with a larger jaw, a bowed member notched at its extremities, which is strained and held in engagement with the base flange of the rail by said last named jaw, and a foot member provided with a tie-abutting flange and with a tongue which intervenes between the yoke and the under surface of the base flange of the rail, the portion of said spring member between the notched extremities thereof diverging from the rail in the direction backwardly from the tie.
16. An anti-creeper comprising a flat bar of metal formed at one end with a jaw to engage one edge of the base flange of a rail, and at the opposite end with a larger jaw, a bowed member notched at its extremities, which is strained and held in engagement with the base flange of the rail by said last named jaw, and a foot member provided with a tie-abutting flange and with a tongue which intervenes between the yoke and the under surface of the base flange of the rail, the yoke being formed with a depressed seat to receive the tongue of the foot member.

HIRAM H. SPONENBURG.
